UNITED STATES PATENT OFFICE

JOSEPH ANDREW CHAMBERS, OF MEMPHIS, TENNESSEE

DESIGN FOR AN OIL-STATION BOOTH

Application filed March 3, 1930. Serial No. 34,720. Term of patent 14 years.

To all whom it may concern:

Be it known that I, JOSEPH A. CHAMBERS, a citizen of the United States, and a resident of Memphis, county of Shelby, and State of Tennessee, have invented a new, original, and ornamental Design for Oil Station Booth, of which the following is a specification, reference being had to the accompanying drawing, forming a part thereof:

Figure 1 is a front perspective view of an

oil station booth showing my new design, and

Figure 2 is a rear perspective view of the same.

I claim:

The ornamental design for an oil station booth, as shown.

In testimony whereof I affix my signature.

JOSEPH ANDREW CHAMBERS.
